Att. ney.

UNITED STATES PATENT OFFICE

EDWIN M. S. CORLISS, OF BUFFALO, NEW YORK

ESCAPEMENT DEVICE FOR SUBMARINES

Application filed November 3, 1928. Serial No. 316,974.

This invention relates to improvements in escapement devices for submarines and the like designed to permit the escape of the occupants in the event the craft is disabled while submerged.

One of its objects is the provision of a simple and efficient escapement device of this character by which the occupants of the disabled vessel may readily effect their own escape.

A further object of the invention is to provide a life saving device for submerged vessels including a buoyant member or float having novel means controllable from within the same for effecting its release from the vessel.

In the accompanying drawings:—

Figure 1 is a fragmentary section view of a vessel showing my improved escapement device installed therein. Figure 2 is an enlarged horizontal section thereof taken on line 2—2, Figure 1. Figure 3 is a sectional view of a modified form of the buoyant member or float.

Similar characters of reference indicate corresponding parts throughout the several views.

By way of example, my invention has been shown as installed in one of the compartments of a submarine, 10 indicating the deck 30 and 11 the bottom wall of the compartment. Built into the latter and extending from the deck to its bottom wall is an upright cylindrical tube or tank 12 closed at its lower end and having an opening 13 at its upper end normally closed by closures 14 and 15, the closure 14 being in the form of a vertically swinging hatch cover adapted to be opened through the medium of a cable 16 connected to a windlass drum 17 mounted in a convenient place within the submarine-compartment. This hatch cover is only open when the submarine is disabled and when the occupants thereof desire to effect their escape. In its side wall adjacent its upper end, the tank 12 has an opening 18 normally closed and sealed water-tight by a cover 19 having suitable latches 20 thereon by which the cover may be removed or locked from either within or outside of the tank.

Contained within the tank 12, which is

adapted to be filled with water, is a buoyant member or float 21 which is preferably of hollow cylindrical construction with rounded ends and of a size to accommodate one or more persons. This float is movable into and out

55 of the tank through the opening 13 of the latter and is guided into place by suitable brackets 22 secured to the inner side walls of said tank. In its side wall adjacent its upper end,

the float has an opening 23 in line with the 60 tank-opening and normally closed watertight by a door or cover 24 preferably having inwardly beveled edges to seat snugly in its correspondingly beveled opening and carrying latches 25 operable from either side of

65 the float for securely fastening the door in place. For the purpose of supporting the door 24 when opened, a lateral guide track 26 may be provided on the exterior side of the float, as seen in Figure 2. When opening this

70 door, it is pulled or pushed outwardly and thence swung to one side of the float-opening 23. In its top the float may be provided with a port hole 27 through which the occupants may observe their position and through which signaling devices may be ejected, if desired.

75 Revolvably mounted on the upper end of the float 21 is the closure or valve member 15 which is adapted to engage a tapered seat 28 formed in the lower portion of the tank-opening 13. This valve-closure prevents leakage of water into the float when the hatch cover or closure 14 is opened and it is free to turn axially to permit a relative movement

80 of the float and its closure and thereby enable the float-opening 23 to be readily brought into line with the tank-opening. As shown in Figure 1, the valve-closure is journaled on a stem 29 rising centrally from the upper end

85 of the float and a ball-bearing 30 may be interposed between these parts. This stem is preferably of hollow form to provide an inlet passage 31 to which is connected a pipe 32 arranged in the upper end of the float and passing through its wall where it discharges into

90 the tank 12. A valve 33 interposed in this pipe serves to control the passage of water from the sea into the tank. When the occupant of the float is ready to make his escape, he

95 opens the valve 33, causing the water from 100

the sea to rush into the tank so that the pressure of the water on either side of the valve-closure 15 is equalized and the float is free to make its egress from the tank.

- 5 To assist the initial opening of the valve-closure 15 in effecting the escapement of the float from the tank, a lift screw 34 is fitted centrally in the lower end of the float and extends through the same, terminating at its 10 lower end in a head 35 engaging the bottom wall of the tank, as seen in Figure 1. The upper or inner end of this screw engages a threaded collar 36 secured to the platform 37 of the float, and a hand wheel 38 is provided for enabling the occupants to turn the screw. By turning the latter to move downwardly, a lifting effort is transmitted to the float which in turn lifts its valve-closure off the seat 28.
- 15 The unseating of the hatch cover 14 is likewise adapted to be assisted by screw pressure, and for this purpose a screw 39 is provided which is threaded into the deck 10 of the craft and bears at its upper end against the under- 20 side of the hatch cover at a point opposite its hinged end. The lower end of the screw has a hand wheel 40 thereon by which the occupants of the disabled submarine may effect its operation. It is to be understood, that in 25 the event of the craft becoming disabled or sunk, the hatch cover is opened first and is kept open during the life saving operations, there being no occasion to close it after once opening it.
- 30 In order to hold the float 21 captive after its leaving the tank 12 and enable it to be drawn back into the latter to effect, by successive operations, the rescue of all the occupants of the craft, a cable 41 is employed 35 which is connected at one end, by a bail 42 with the lower end of the lift-screw 34 or other suitable part of the float, while its other end is joined to a windlass drum 43 disposed alongside the lower end of the tank.
- 40 In passing from the screw to the windlass drum, the cable passes through a packing gland 44 in the tank.

45 Draining of the tank 12, which must be done after returning the float 21 thereto 50 after each rescue operation so as to enable the remaining occupants to be transferred from the submarine-compartment to the float through the alining openings 13 and 23, is accomplished by means of a drain cock 45 fitted in the lower end of the tank and discharging into a suitable compartment for receiving it or pumped directly back into the sea.

55 As a supplementary means for filling the 59 tank 12 with sea water when ready to discharge the float therefrom, a pipe 46 is connected at one end to the submarine-deck 10 and at its other end to the tank, a valve 47 being interposed therein to control it.

60 The passage 31 formed in the stem 29 of

the float may serve as a means for connecting a compressed air line thereto for the purpose of assisting in the raising of the disabled craft.

65 If desired, the float may be double-walled, as shown at 48 in Figure 3, the resulting compartment 49 between the walls being adapted to receive compressed air to increase its buoyancy.

70 The operation of the improved escapement means is as follows:—

75 Assume that a submarine equipped with the invention has become disabled and has sunk, and the tank 12 to be empty. The hatch door 14 is first opened through the medium of the screw 39 and windlassing cable 16. The covers 19 and 24 of the tank and float, respectively, are then opened and one or more occupants of the craft enter the float through the alining openings 13 and 23, closing the 80 covers behind them. Thereupon the sea water is allowed to enter the tank through the valve-controlled passage 31 and pipe 32, and the lift-screw 34 is actuated to partially elevate the float and lift its valve 15 off the seat 28. As the water enters the tank, the float is gradually buoyed up and discharged from the latter, the float rising to the surface of the water where the occupants may signal their distress or if their position permits it, effect 85 their own safety, after which the float is drawn back into the tank by means of the cable 41, its valve closure 15 sealing the tank at its upper end. The tank is then drained and the same steps as above enumerated are then carried on to effect the saving of the other 90 occupants.

95 While manifestly simple and compact in construction, this device can be readily installed on existing submarines and other craft without materially altering their construction, and it affords the ready escape of all 100 the occupants of the craft.

105 I claim as my invention:—

- 110 1. An escapement device for submarine craft and the like, comprising a chamber arranged within the craft and having openings to the exterior and interior of the latter, a buoyant occupant-receiving member disposed within said chamber and having a 115 hollow stem projecting upwardly from its top side, the upper end of the stem-passage being adapted for communication with the sea water, a valve-closure applied to said stem for normally engaging the opening in 120 said chamber leading to the exterior of the craft, said buoyant member having an opening therein in line with the opening leading to the interior of the craft, closures for said last-named openings, and a valved-pipe contained within the buoyant member and connected at one end with the stem-passage and communicating at its other end with said chamber.

- 125 2. An escapement device for submarine 130

craft and the like, comprising a chamber arranged within the craft and having openings to the exterior and interior of the latter, the opening leading to the exterior of the craft including a downwardly-tapering seat, a buoyant occupant-receiving member disposed within said chamber and having an opening therein adapted to be alined with the opening leading to the interior of the craft, a valve-closure revolvably mounted at the upper end of said member and normally engaging said tapered seat, closures applied to the alining openings of said chamber and said buoyant member, and means operable from within said member for controlling the admission of sea water to the chamber to effect the floating of the buoyant member therefrom.

3. An escapement device for submarine craft and the like, comprising a chamber arranged within the craft and having openings to the exterior and interior of the latter, the opening leading to the exterior of the craft including a downwardly-tapering seat, a buoyant occupant-receiving member disposed within said chamber and having an opening therein adapted to be alined with the opening leading to the interior of the craft, a valve-closure revolvably mounted at the upper end of said member and normally engaging said tapered seat, closures applied to the alining openings of said chamber and said buoyant member, a lift-screw applied to the lower end of the latter and normally abutting at its lower end against the bottom of the chamber to effect the initial unseating of the valve-closure from its seat, and means operable from within the buoyant member for controlling the admission of sea water to the chamber to effect the floating of said member therefrom.

4. An escapement device for submarine craft and the like, comprising a chamber arranged within the craft and having openings to the exterior and interior of the latter, the opening leading to the exterior of the craft including a downwardly-tapering seat, a buoyant occupant-receiving member disposed within said chamber and having an opening therein adapted to be alined with the opening leading to the interior of the craft, a valve-closure revolvably mounted at the upper end of said member and normally engaging said tapered seat, closures applied to the alining openings of said chamber and said buoyant member, a lift-screw applied to the lower end of the latter and normally abutting at its lower end against the bottom of the chamber to effect the initial unseating of the valve-closure from its seat, means operable from within the buoyant member for controlling the admission of sea water to the chamber to effect the floating of said member therefrom, and a captive cable connected to said lift-screw.

5. An escapement device for submarine craft and the like, comprising a chamber arranged within the craft and having openings to the exterior and interior, thereof, the opening leading to the exterior of the craft including a downwardly-tapering valve seat, a buoyant occupant-receiving member disposed within said chamber and having an opening therein adapted to be alined with the opening leading to the interior of the craft, a hatch cover applied to said exterior opening, a winding drum including a cable operatively connected to said hatch cover for opening it, screw-pressure means for effecting the initial opening of the hatch cover, a valve-closure revolvably mounted at the upper end of the buoyant member and normally engaging said tapered seat, said buoyant member being free to revolve within its chamber when the valve-closure is seated to aline its opening with that of the interior opening of said chamber, closures applied to said alining openings, a lift-screw applied to the lower end of the buoyant member and normally abutting at its lower end against the bottom of the chamber to effect the initial unseating of the valve-closure from its seat, means operable from within the buoyant member for controlling the admission of water to the chamber to effect the floating of said member therefrom, and a captive cable connected to said lift-screw.
